WARP STOP MECHANISM FOR LOOMS.

Application filed February 14, 1928. Serial No. 254,201.

This invention relates to warp stop mechanism for looms wherein a normally operated detecting member is adapted to be arrested in its movement when a warp thread breaks or becomes too slack for weaving purposes, and thereupon effect loom stoppage.

Mechanical warp stop mechanisms are of two general types, one in which the detecting member is given a movement in the general direction of the warp threads, and the other in which the detecting member is given movement transversely of the loom.

The present invention is more particularly directed to the second of the above types of warp stop mechanisms, and in one aspect of the invention it is a further development of the warp stop mechanism shown and described in the patent to Harry A. Davis and Arthur S. Johnson, No. 1,538,625, dated May 19, 1925.

One of the objects of the present invention is to simplify the warp stop mechanism of the transversely movable detector bar type and to effect loom stoppage when a drop wire fails to be normally supported by a warp thread.

In the warp stop mechanism of the Davis and Johnson patent a series of yieldingly mounted actuators were connected to the transversely movable detector bars, and upon tilting movement of one of the actuators relative to its carrying means, a train of mechanism was set in operation to effect loom stoppage, such mechanism including a stop finger and associated parts. With respect to this feature the present invention comprehends the yieldingly operated actuators for one or more detecting bars and a stop bar, one at each side of the yieldingly mounted actuator, so that should an actuator be held from movement by stoppage of the detector bar, one of the stop bars will act through a train of mechanism to effect loom stoppage.

It is now the ordinary practice to connect the actuator to the detecting bar by a link which may be positively connected to the detecting bar or detachably connected thereto by a pin and slot through a link carried by one of the parts to be connected. On one hand, it is desirable at times to disconnect the actuator from its detecting bar, so that the general practice has now been to detachably connect the actuator and detecting bar

by a link having an open-ended slot to engage a pin on the detecting bar. This construction, however, introduces an objection in that the loom attendant while piecing up warp threads or working about the stop motion is liable to accidentally detach the connection between the actuator and detector bar, and the present invention seeks to avoid this accidental detachment by a manually operated lock which will afford protection against accidental disconnection and yet permit intentional disconnection of the actuator and detecting bar.

The invention and novel features thereof and new combination of parts will best be made clear from the following description and the accompanying drawings of one embodiment thereof.

In the drawings:

Fig. 1 is a perspective view at one end portion of a warp stop mechanism embodying the present invention;

Fig. 2 is an elevation of the warp stop mechanism embodying the present invention, some of the parts being broken away and one of the drop wires being shown as arresting a detector bar;

Fig. 3 is a sectional side elevation with some of the parts omitted, showing more particularly the yieldingly mounted bar actuator connected to its detecting bar and the stop bars embracing the actuator;

Fig. 4 is a section on the line 5—5 of Fig. 3 showing the manually operable lock in its detaching position.

As is usual with warp stop mechanisms of the transversely movable detecting bar type, a bracket is secured at each side of the loom for supporting the warp stop mechanism, and in the present instance of the invention, as indicated in Figs. 1 and 2, the loom frame is provided with a bracket support 1 adapted to sustain a bracket 2, one at each side of the loom, and, as usual in warp stop mechanisms, means are provided for effecting adjustment of the bracket 2 on its supporting member. In the present instance of the invention, a bolt 3 and appropriate slots 4 and 5 serve to adjustably support each of the brackets 2, one at each side of the loom, in the position of adjustment.

Connected to the upstanding portion 6 of each of the brackets 2 are the side members 7 of the warp stop mechanism. Extending between the side members 7 are the warp

supports 8 and 9 over which the warp threads a pass and by which they are supported. The parts so far described are of usual construction and need no further description.

Extending between the side members 7 are the fixed toothed detecting bars 10 each of which has associated with it a transversely movable toothed detecting bar 11 10 which may be guided in its transverse movement of the loom by a slot formed in the fixed detecting bar 10. Obviously there may be any number of detecting bars appropriate to the character of the loom in use and number 15 of warp threads, and in the present instance of the invention there are shown four of such detecting bars cooperating with a corresponding series of drop wires.

The drop wires 12 may likewise be of 20 usual construction and as shown in the present instance of the invention they are of the general hairpin type of drop wire, each having a slotted opening at its upper end through which the toothed detecting bars 25 extend, and the lower portion of each drop wire is provided with an opening through 25 which a warp thread passes and by which the drop wire is held in its normally raised position during weaving. The form of the 30 drop wire that has been described is preferred, though any usual form of drop wire may be employed, the essentials in this respect being that a series of drop wires has 35 associated with it a toothed detecting bar and when the drop wire is normally held in raised position by the warp thread engaged by it, it will permit free movement of the 40 movable detecting bar, but should a warp thread become broken or too slack for weaving purposes, the drop wire will engage between the teeth of the movable detecting bar and arrest its movement as usual in this type of warp stop mechanisms.

Pivottally mounted on each of the side 45 supports or brackets 7 is a stringer cap which, in normal position during weaving, holds the detecting bars in place. In the present instance of the invention each stringer cap 15 is provided with a slotted 50 lug or downward extension 16 which embraces a pivot or stud 17 mounted at one end of each of the side supports or brackets 7, whereby the stringer caps may be turned from their normal position overlying the detector bars to a substantially horizontal position. An adjusting screw 18 is associated 55 with each stringer cap and threaded into the pivot stud 17, whereby the stringer caps may be raised or lowered bodily.

60 Mounted in suitable bearings 23, one at each side of the stop motion is a rock shaft 24 to which are secured the rockers 25, and the desired connection between the rockers and the rock shaft may be readily effected 65 by means of a locking screw 26, the construc-

tion being such that as the rock shaft is given its rocking movement the series of rockers will be rocked therewith.

As indicated more particularly in Figs. 3 and 4, each of the rockers 25 is provided 70 with a fulcrum seat 27, one at each side of the vertical plane passing through the rocking axis of the rockers. Mounted upon each of the rockers 25 is a detecting bar actuator 28, each of which has two pins 29 on its 75 lower portion adapted to be seated in the fulcrum recesses 27 of the associated rocker 25, and by a spring 30 connected at its upper end to the actuator 28, as by a pin 31, and at its lower end by a part 32 carried by 80 the associated rocker, the actuators are normally held in their operating position as indicated in Fig. 3. Each of the detecting bar actuators 28 is connected to its associated detecting bar and should the latter be arrested in its movement by a drop wire, its actuator 28 will likewise be arrested while the rocker itself continues its movement, a condition which is effected by means of the yielding connection or spring 30 between it 90 and its rocker.

Loosely mounted upon the rock shaft 24 are the stop bar carriers 33, two at each side of the warp stop mechanism, as indicated more clearly in Fig. 1. Extending 95 between the stop bar carriers 33 are the stop bars 34 which may be appropriately secured to the associated carriers by means of set screws 35, and the two stop bars 34 normally embrace the actuators or series of 100 actuators 28, and, as will presently appear, yielding means are provided for holding the stop bars 34 in the described relation to the actuators.

One of the stop bars 34 has secured there- 105 to the link 36 which is provided with a slot 37 into which the opposite or companion stop bar 34 extends.

Mounted in the slotted portion of the link 36 is a plunger 38 which is normally under 110 the influence of a spring 39 serving to hold the end of the plunger against the stop bar 34 in the slot of the link, with the result that the two stop bars are normally held in yielding relation against opposite sides of 115 the actuator or actuators. The plunger 38 may be appropriately carried by a sleeve 40 which may be secured by a screw bolt 41 to the link 36, and bearing upon the enlarged portion 42 of the plunger is the end 120 of a flexible sheathed wire 43, which serves to transmit longitudinal movement of the plunger to thereby call into action the stop mechanism. The details of the stop mechanism are not herein shown, as they may be 125 of any appropriate character, as, for instance, that disclosed by the Davis and Johnson patent, hereinbefore mentioned.

From the construction thus far described it will be apparent that should one of the 130

detecting bar actuators be arrested in its movement, it will act through one of the stop bars 34 to arrest such stop bar, whereupon the other stop bar which is moved by the actuators will act, either through the link 36 or the stop bar in the slot of the link, to cause relative movement of the plunger and the link to thereby move the sheathed wire 43 and effect loom stoppage. This condition is illustrated in Fig. 2, wherein the stop bar at the right has been arrested, while the other stop bar at the left continues to move, with the result that the link 36 is moved by the stop bar 34 to which it is secured to cause relative movement between the link and the plunger 38 and effect loom stoppage as described.

Each of the actuators 28 contained in the warp stop mechanism is detachably connected to its transversely movable detector bar so that the two may be disconnected at will, and the connecting means has associated therewith a manually operable lock whereby accidental disconnection of the actuator and its detecting bar is prevented. This locking feature may take various forms, but as indicated in the present instance of the invention and as more clearly shown by Figs. 3 and 4, the actuator 28 is provided with a manually operable slide 44, the lower end portion of which is bifurcated, as at 45, to engage a pin 46 connected to the movable detecting bar, the construction being such that when the slide 44 is moved downwardly relative to the connected actuator, the bifurcated end 45 will engage the pin 46 and upon movement of the actuator impart movement to the detecting bar.

As indicated in Figs. 3 and 4, the actuator 28 is provided with the pins 47 which engage the elongated slots 48 in the slide 44, the enlarged overlying heads 49 of the pins acting to hold the slide and actuator in operative relation. When the slide 44 is moved downwardly to engage the pin of its associated detector bar, it is important that such connection be not accidentally disturbed by the loom attendant in piecing up or manipulating parts of the loom about the warp stop mechanism, and one means to this end consists in a manually operable lock to prevent such accidental disconnection between the actuator and its associated detecting bar.

A good form of such lock is shown by Figs. 3 and 4, wherein the slide 44 has mounted thereon a projection 50 which may be suitably formed as a sphere held in a suitable recess in the slide 44 and adapted to engage one of two openings 51, 52 in a strap 53 which overlies the projection or ball 50 in the slide and is held in place by engaging beneath the enlarged heads 49 of the pins 47. The strap 53 is appropriately formed as a leaf spring, with the result that when the slide 44 is in its upper position as

indicated in Fig. 4 and the ball or sphere 50 is engaged with the upper opening 51 in the strap, the slide will be held in its locked position, thus freeing the connection between the actuator and its associated detecting bar; and similarly, when the slide 44 is in its lowered position as indicated in Fig. 3, to which position it may be readily moved by manual effort, the sphere or ball 50 will engage the lower opening 52 in the strap and maintain the actuator locked to its detecting bar.

Any suitable means may be employed for imparting to the rock shaft 24 and the rockers 25 the desired rocking movement, but in the present instance of the invention the rock shaft 24 has secured thereto an arm 54, the end portion of which is provided with a slot 55 which is engaged by a pin 56 connected by an arm 57 with the upper end portion 58 of an actuating member 59 which may be given its desired movement to effect actuation of the rock shaft and rockers from any suitable going part of the loom, but as such details form no part of the present invention they are not herein further described and are moreover well known in the art.

It is sometimes expedient to position the fixed member 10 of the detector mechanism by inserting such fixed member endwise from either side of the stop motion and then inserting the movable member 11, which carries the pin 46 from the right of the stop motion, as shown. This is rendered possible in the present invention by forming the fixed member 10 with a reduced portion 60 at its end, so that the movable member may be inserted from the right of the stop motion, as shown, the pin 46 at such time being freely movable along the reduced portion of the fixed member.

What is claimed is:

1. In a warp stop mechanism for looms, the combination of a series of drop wires normally supported by the warp threads during weaving, a transversely movable toothed detecting bar adapted to be arrested by a drop wire, a rocker, a detector bar actuator yieldingly mounted on the rocker and connected to the toothed detecting bar, a stop bar at each side of the actuator, yielding means normally acting to maintain the stop bars in engagement with the detector bar actuator for movement therewith, and means actuated by one of the stop bars to effect loom stoppage.

2. In a warp stop mechanism for looms, the combination of a series of drop wires normally supported by the warp threads during weaving, a transversely movable toothed detecting bar adapted to be arrested by a drop wire, a rock shaft and actuating means therefor, a detector bar actuator yieldingly connected to the rock shaft for

- rocking movement therewith, a stop bar at each side of the actuator, a stop link secured to one of the stop bars for movement therewith, yielding means acting through 5 the other stop bar to maintain both stop bars in engagement with the detecting bar actuator, and means actuated by movement of the link with its connected stop bar to cause the other stop bar to effect loom stoppage.
- 10 3. In a warp stop motion of the transversely movable toothed bar type, a series of drop wires, a yieldingly mounted bar actuator and operating means therefor, a stop bar at each side of the bar actuator, a link connected to one of the stop bars for movement therewith and having relatively movable connections with the other stop bar, yielding means normally acting between the two stop bars to maintain them in engagement with the bar actuator that the link and stop bars may move with the bar actuator, and means actuated by relative movement of the link and stop bar movably connected therewith for effecting loom stoppage.
- 15 4. In a warp stop mechanism for looms, the combination of a series of drop wires, a transversely movable toothed detecting bar, a yieldingly mounted bar actuator and operating means therefor, a stop bar at each side 20 of the bar actuator, a link secured to one of the stop bars and having a slot connection with the other stop bar, yielding means acting through the link upon one of the stop bars to maintain both stop bars in engagement with the toothed bar actuator, and means actuated by relative movement of the stop bar in the slot of the link to effect loom 25 stoppage.
5. In a warp stop mechanism for looms, the combination of a series of drop wires, a transversely movable toothed detecting bar, a yieldingly mounted bar actuator and operating means therefor, a stop bar at each side of the bar actuator, a link secured to one 30 of the stop bars and having a slot connection with the other stop bar, a yieldingly mounted plunger connected to the slotted link and bearing upon the stop bar therein to maintain the two stop bars in engagement 35 with the actuator, and means actuated by the plunger when moved longitudinally relative to the link by its adjacent stop bar to effect loom stoppage.
6. In a warp stop mechanism for looms, the combination of a series of drop wires, a transversely movable toothed detecting bar, a yieldingly mounted bar actuator and operating means therefor, a stop bar extending transversely of the bar actuator at 40 each side thereof, a link secured to one of the stop bars and having a sliding connection with the opposite stop bar, a plunger carried by the link and yieldingly impelled into engagement with said last named stop bar and acting through the link to maintain 45
- the stop bars in engagement with the actuator, and means actuated by the plunger when moved relative to the link to effect loom stoppage.
7. In a warp stop mechanism for looms, 70 the combination of a series of drop wires, transversely movable detecting bars, a rock shaft carrying a series of rockers, detecting bar actuators mounted on the rockers and each connected with a detecting bar, a stop bar extending transversely of the actuators at each side thereof, a link secured to one of the stop bars and having a sliding connection with the other stop bar, a yielding member carried by the slotted portion of the link 75 and bearing against the adjacent stop bar, and means actuated by the yielding member to effect loom stoppage when the yielding member and slotted link are relatively moved by one of the stop bars. 80
8. In a warp stop mechanism of the transversely movable detector bar type, the combination of a series of drop wires normally supported by the warp threads during weaving, a detector bar provided with a series of 85 teeth projecting from its upper edge and having a detecting movement lengthwise in a direction transversely of the loom and adapted to be arrested by a fallen drop wire, a rocker, a link connected to the transversely 90 movable toothed detector bar for moving it transversely of the loom, two independently mounted rigid stop bars extending from front to rear of the warp stop mechanism, and normally operated in a direction lengthwise of the toothed detector bar by rocking movement of the rocker, a spring normally 95 acting between the rigid stop bars to cause them to move in unison with the rocker, and transmission mechanism actuated by one of 100 the stop bars when it is arrested by the occurrence of a warp fault to effect loom stoppage. 105
9. In a warp stop mechanism for looms, 110 the combination of a series of drop wires normally supported by the warp threads during weaving, a series of transversely movable detector bars, a rocker for imparting transverse movements to the series of detector bars, two stop bars independently 115 mounted and extending in a direction transversely of the series of detector bars one at each side of the rocker, a spring acting normally to yieldingly hold the stop bars for movement in unison with the rocker, and mechanism actuated when either stop bar is arrested to cause loom stoppage. 120
10. In a warp stop mechanism for looms, 125 the combination of a series of drop wires normally supported by the warp threads during weaving, a rock shaft, a rocker mounted on the rock shaft, a transversely movable toothed detector bar actuated from the rocker, independent stop bar carrier arms loosely mounted on the rock shaft, stop bars 130

mounted on the carrier arms above the rock shaft one at each side of the rocker, a spring yieldingly acting to hold the stop bars towards each other, and a train of mechanism actuated by either stop bar when it is arrested to effect loom stoppage.

11. In a warp stop mechanism for looms, the combination of a series of drop wires normally supported by the warp threads 10 during weaving, a rock shaft, a rocker mounted on the rock shaft, a transversely movable toothed detector bar actuated from

the rocker, independent stop bar carrier arms loosely mounted on the rock shaft and diverging upwardly therefrom, stop bars mounted on the carrier arms above the rock shaft one at each side of the rocker, a spring yieldingly acting to hold the stop bars towards each other, and a train of mechanism actuated by either stop bar when it is arrested to effect loom stoppage. 15 20

In testimony whereof, I have signed my name to this specification.

CARL D. BROWN.
